UNITED STATES PATENT OFFICE.

ALVIN DAVIS PUFFER, OF MEDFORD, ASSIGNOR TO A. D. PUFFER'S SONS,
OF BOSTON, MASSACHUSETTS.

FAUCET.

SPECIFICATION forming part of Letters Patent No. 318,801, dated May 26, 1885.

Application filed October 14, 1884. (No model.)

To all whom it may concern:

Be it known that I, ALVIN DAVIS PUFFER, a citizen of the United States, residing at Medford, in the county of Middlesex and State 5 of Massachusetts, have invented certain new and useful Improvements in Faucets; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to means for preventing injury to liquids contained in metal vessels containing surfaces liable to oxidation or corrosion by the action of said liquids; and it consists in covering the portions of the vessel exposed to contact with the liquid with a plate.

20 In my method I protect the parts by a covering of non-corrosive material of such thickness that it remains intact under the ordinary 25 wear of the plug and case, the portions of said plug and case not exposed to the liquid being of much harder metal than the protecting-plates, thereby constituting bearings of sufficient hardness to allow of long use of the 30 faucet and protect the non-oxidizing metal from wear.

35 In faucets where the plug makes but a partial revolution—that is, less than half a turn—the protecting metal may be applied only to the portion of the body of the faucet exposed to the liquid. In other instances the protecting metal will extend entirely around the plug.

40 The drawings accompanying this specification represent in Figure 1 a vertical and in Fig. 2 a horizontal section on line $y-y$ of a single or ordinary faucet containing my invention, while Fig. 3 is a vertical and Fig. 4 a horizontal section on line $x-x$ of a double or compound faucet so furnished. Fig. 5 is a section of part of the case of the single faucet. Fig. 45 6 is a view of the compound metal strip, to be explained.

In Figs. 1 and 2 the body or case of the

faucet is shown at A, its plug at B, its cap at 50 C, the liquid-way of the case being shown at a, and of the plug at b. In this instance the plug describes less than half a revolution; hence the protecting metal plate, which is shown at D, need extend but partially around 55 the interior of the case, as shown by heavy black line in Fig. 2. In applying this plate of protecting metal (which I prefer to make of pure silver) a good method is to counterbore the interior of the case from the top, as 60 shown in Fig. 5 at e, and insert the protecting-plate D in the form of a tube in the lower part of the counterbore. The upper part of the counter is filled with a ring, E, of the same metal as the body or case A, and this ring E, 65 to obtain desired strength, is preferably of considerably greater thickness than the plate D. The tube D and ring E may be secured firmly in place by the method known as "pure 70 tin sweating."

In putting my invention into practice a good way to proceed in making the single faucet would be to employ two strips, D D', of metal, of considerable length, (see Fig. 6,) one, D', of practically the same material as the case of 75 the faucet, and the other, D, of silver or other non-corrosive metal, and braze the edges of these strips together. The width of the compound strip G is such as to form a tube to fill the lower part of the counterbore e, and a 80 piece of the proper length is to be cut from the strips for each faucet.

In Figs. 3 and 4 of the drawings the two plugs of a combination-faucet are shown, the outer one at A and the inner at B, while the 85 outer case or body of the faucet is shown at H.

The liquid way or port of the plug A is shown at A', and of the plug B at B'.

The liquid-passages of the outer case, H, adapted to operate with the port A', are shown 90 at a' a', &c., as in this instance, extending radially entirely about such case; hence it is essential that the port of the plug A opposite such passage shall be provided with a protecting-plate extending entirely about the outer 95 periphery of the said plug A. This plate is in the form of a tube, F, of non-corrosive metal, inclosing and secured to the lower part

of the plug A. In the present instance the inner plug, B, has but a short movement—that is, one similar to the plug B of Figs. 1, 2, and 3. For this reason the protecting-plate in this 5 case may be made and applied as thus shown in Figs. 1, 2, and 3.

As before stated, the non-corrosive metal plate or tube F is presented to the action of the liquids, thereby avoiding injury to the 10 latter, while the remainder of the outer periphery of the plug is composed of a hard metal to resist wear.

In all these forms the silver plate faces the outlet of the way or ways.

15 I am aware that it is not new to make a faucet-plug wholly of non-corrosive material; also, that it is not new to provide a faucet with a lining of tin, zinc, or other not easily oxidizable material facing the liquid-ways of the 20 plug; also, that it is not new to make an interior lining of the faucet from non-corrosive white-metal, the same being a mixture of tin, nickel, and regulus of antimony. I do not claim any of these devices; but,

25 Having thus described my invention, what I claim as new, and desire to secure by Letters Patent, is—

1. A faucet provided with a silver protecting-plate, the latter being arranged facing the outlet of the liquid-way, substantially as set 30 forth.

2. In combination with a faucet-plug, a silver protecting-plate on the inside of the faucet-case, arranged facing the outlet of the liquid-way b of the plug, substantially as set 35 forth.

3. A protecting-plate, D, set into the counterbored inner face of a faucet-case facing the liquid-ways of the plug, in combination with the ring E, which is set into the same 40 counterbore and holds said plate in place, said ring being soldered to said faucet-case, substantially as set forth.

4. A faucet-plug of hard metal, provided with a countersunk plate or plates of non-corrosive metal, which are presented to the liquid for the purpose of protecting the body of said plug, substantially as set forth. 45

In testimony whereof I affix my signature in presence of two witnesses.

ALVIN DAVIS PUFFER.
